UNITED STATES PATENT OFFICE.

EMIL PASSBURG, OF BERLIN, GERMANY.

VACUUM-DRIER.

No. 830,521.

Specification of Letters Patent.

Patented Sept. 11, 1906.

Application filed July 27, 1905. Serial No. 271,417.

To all whom it may concern:

Be it known that I, EMIL PASSBURG, a subject of the King of Prussia, German Emperor, residing at Berlin, Germany, have invented certain new and useful Improvements in Vacuum-Driers, of which the following is a specification.

This invention relates to improvements in vacuum-driers.

The known vacuum-driers in which heated rotary drying-drums are used are highly suitable for drying various liquid or semi-liquid substances, but are not suitable for treating substances the solid constituents of which rapidly settle or form deposits, as is, for instance, the case with pasty mixtures, such as paints and the like. With semi-liquid masses of this kind the deposits formed settle at the bottom of the vacuum-chamber in more or less thick layers, with which the drum does not come into contact, owing to the fact that for efficient working the said drum must only extend into the mass to a comparatively slight depth, and therefore only acts on the upper liquid layers, which gradually become poorer in mechanical admixtures, so that uniform and complete drying is prevented.

The object of this invention is to remove this disadvantage and to allow of producing with perfect efficiency vacuum-drying apparatus of the kind referred to for drying liquid substances in which sediments or deposits are rapidly formed. The means adopted for this purpose according to the present invention substantially consist in continuously stirring or agitating the liquid mass at the bottom of the vacuum-chamber and that the solid constituents about to be deposited are dispersed and brought into contact with the walls of the rotary drum.

The stirring and agitating of the liquid mass can be effected by means of any suitable known device—for instance, by means of the device illustrated in the annexed drawings, in which—

Figure 1 is a cross-section, and Fig. 2 a longitudinal section, of the improved apparatus. The vacuum-chamber *a* is provided at its lower part with bearings for the axles *b*, which are provided with blades *c* or the like, so arranged that they mesh with each other and that during the rotation of the axles the outer edges of the lower blades pass within a very short distance of the bottom of the chamber *a*, and thus effectively prevent the formation of a deposit on the said bottom.

One of the axles *b* is connected, by means of the gear-train *e*, with the axle *d* of the drying-drum and serves to drive the other axles *b* by means of suitable toothed wheels. The drying-drum may be heated by any suitable means, such as a hot fluid, introduced through a pipe *f* and discharged through a pipe *g*, both of which pipes may extend through the axles *b* of the drying-drum.

What I claim as my invention, and desire to secure by Letters Patent of the United States, is—

1. In an apparatus for drying liquid substances containing rapidly-settling solid constituents, the combination of a casing to hold the liquid, an inner drum adapted to rotate through the liquid, and means independent of the drum for stirring the liquid at the bottom of the casing.

2. In an apparatus for drying *in vacuo* liquid substances containing rapidly-settling solid constituents, the combination of a cylindrical casing to hold the liquid, an inner drum adapted to rotate through the liquid, and blades adapted to rotate through the liquid between the drum and the bottom of the casing.

In testimony whereof I affix my signature in presence of two witnesses.

EMIL PASSBURG.
